[57] CLAIM

The ornamental design for a combined bed and headboard unit, substantially as shown and described.

DESCRIPTION

FIG. 1 is a perspective view of the combined bed and headboard unit incorporating our novel design;

FIG. 2 is a front view of the unit in FIG. 1;

FIG. 3 is a side view of the unit in FIG. 1; and

FIG. 4 is a top view of our new combined bed and headboard unit.

The appearance of the side of the combined bed and headboard unit which is not shown in the drawing is identical with the appearance of the side shown in FIG. 3.

The rear of the unit is conventionally plain and unornamented.
